UNITED STATES PATENT OFFICE.

EDWARD W. ROTHFUS, OF ROCHESTER, NEW YORK, ASSIGNOR TO ERROR-NO, INC.,
OF ROCHESTER, NEW YORK, A CORPORATION OF NEW YORK.

COPY-HOLDER.

1,390,723.

Specification of Letters Patent. Patented Sept. 13, 1921.

Application filed July 12, 1920. Serial No. 395,683.

To all whom it may concern:

Be it known that I, EDWARD W. ROTHFUS, a citizen of the United States of America, residing at Rochester, in the county of Monroe and State of New York, have invented certain new and useful Improvements in Copy-Holders, of which the following is a specification.

My invention relates to copyholders of the type generally used in connection with typewriters, and embodying a vertically movable copy support adapted to be elevated by the operator to bring successive lines of writing into view, and the purpose of the improvement is to provide a device for effectively cushioning the fall of the copy support when the latter is released and drops to its lowermost position.

In most structures of this class, the copy support is arranged to fall by gravity to its bottom position when released, and various mechanisms have been utilized for balancing the copy support, in order to prevent shock and jar, but even with such devices, it is impossible to entirely absorb the shock, particularly where the cushioning means involves an adjustment for different sizes and weights of copyholders. In such designs, it not infrequently happens that the assembler does not make the proper adjustment for the particular size model, and it is the province of the present invention to take care of any such error in assembling, and to supplement the principal cushioning means, by providing a shock absorbing device that will counteract any inaccuracy in the adjustment of the principal cushioning means, and absorb the slight shock or jar that would otherwise result.

A further object of my invention is to afford an efficient, but simple and inexpensive means, which can be cheaply manufactured and assembled, thus making it entirely practical for manufacturing purposes.

The invention includes certain other objects and advantages that will appear clearly from the following description, in conjunction with the accompanying drawing, the features of novelty being pointed out in the 50 claims at the end of the specification.

In the drawing:

Figure 1 is a rear elevation of a well known form of copyholder, showing the application of the invention thereto;

Fig. 2 is a sectional view on line 2—2 of Fig. 1;

Fig. 3 is a horizontal sectional view on line 3—3 of Fig. 1, and

Fig. 4 is a side elevation of the shock absorbing means, removed from the copyholder.

Referring with more particularity to the drawing, A designates the base of a stationary frame, which also includes vertical guide-rods B, while C is a vertically movable copy support which travels on the guide-rods B, and to accomplish this, the copy support C is provided with tubular extensions or curved portions D which embrace the guide-rods B. It is to be understood that suitable instrumentalities are provided for elevating the copy support C step-by-step to expose one line at a time, and when the copy support reaches its uppermost position, or any other position during its upward travel, it may be released to permit it to fall to the lowermost or initial position illustrated in Fig. 1. Since the mechanism just referred to is well known in the copyholder art, and does not form a novel part of my invention, it is unnecessary to make more than brief reference to it, for a proper understanding of the function of the construction now to be described.

The shock absorbing means comprises a resilient tubular member E, preferably made of rubber or other compressible material, and within the tubular member E is a metallic spiral spring F, the lower end of which preferably projects beyond the resilient tube E, as shown in Fig. 2. The shock absorbing means is located at the upper end of the copy supporting member and arranged to engage the upper end of the stationary frame, and in the present embodiment, this is accomplished by locating each resilient tubular member E and spring F immediately over a guide-rod B.

One method of carrying out this result consists of positioning the resilient tube E partially within the upper end of the tubular extension D of the copy support, said tubular extension being bent in sufficiently at its upper extremity to grip the tubular member E, as shown in Fig. 2. The parts are also arranged so that the spring F contacts at its upper end and is held against upward movement by a flange G, which is formed

upon and extends transversely at the top of the copy support C.

Thus the resilient tubular member E and spring F are superposed above the guide-rod B, and coöperate with said guide-rod to cushion the fall of the copy support when it reaches its lowermost position. By arranging the spring with its lower end extending beyond the resilient tube E, the 10 spring and tube successively engage the guide-rod, the spring being first compressed and thereafter the tube. This produces initial and final cushioning actions of increasing resistance, the spring serving to slow down the travel of the copy support, and the resilient tubular member to act as a 15 final cushioning stop which also prevents rebound. The tubular member E acts in the capacity of both a housing and also a 20 support or guide for the side walls of the coil spring, which is thereby retained against improper bending or twisting upon compression.

The particular construction shown may 25 be modified, and this application is intended to cover any departures that may come within the spirit of the invention, and the scope of the following claims.

I claim:

- 30 1. In a copyholder, the combination with a stationary frame and a vertically movable support, of shock absorbing means acting to cushion the fall of the movable support upon the stationary frame, said shock absorbing means comprising a resilient tube and a spiral spring located within the tube, with one end of the spring extending beyond the tube whereby the spring and tube are successively compressed.
- 40 2. In a copyholder, the combination with a stationary frame and a vertically movable support, of shock absorbing means acting to cushion the fall of the movable support upon the stationary frame, said shock absorbing means comprising a resilient tube carried by the vertically movable support and arranged to engage the stationary frame,

and a spiral spring located within the tube with the lower end of the spring extending beyond the tube whereby the spring and tube 50 successively engage the frame and are successively compressed.

3. In a copyholder, the combination with a stationary frame comprising vertical guide-rods, and a support movable vertically 55 on said guide-rods, of shock absorbing means acting to cushion the fall of the support on the guide-rods, said shock absorbing means comprising a resilient tube carried by the support at its upper end and arranged to 60 engage the top of one of said guide-rods, and a spiral spring located within the tube with the lower end of the spring extending beyond the tube whereby the spring and tube 65 successively engage the top of the guide-rod and are successively compressed.

4. In a copyholder, the combination with a stationary frame comprising vertical guide-rods, and a support having tubular extensions engaging said guide-rods and 70 movable vertically thereon, of shock absorbing means acting to cushion the fall of the support on the guide-rods, said shock absorbing means comprising a resilient tube clamped within one of said tubular extensions at its upper end and arranged to 75 engage the top of one of said guide-rods, and a spiral spring located within the tube with the lower end of the spring extending beyond the tube whereby the spring and tube 80 successively engage the top of the guide-rod and are successively compressed.

5. In a copyholder the combination with a stationary frame and a vertically movable support, of shock absorbing means acting 85 to cushion the fall of the movable support upon the stationary frame, said shock absorbing means comprising a resilient body and a spiral spring positioned with reference to the resilient body so that the spring 90 and body are successively compressed.

In witness whereof I hereunto sign my name.

EDWARD W. ROTHFUS.
